[57] CLAIM

The ornamental design for a toolbox having a transparent lid, as shown and described.

DESCRIPTION

FIG. 1 is a perspective view of a toolbox showing our new design, the toolbox having a transparent lid;

FIG. 2 is a front elevational view of the toolbox of FIG. 1;
FIG. 3 is a rear elevational view of the toolbox of FIG. 1;
FIG. 4 is a right end elevational view of the toolbox of FIG. 1, the left end elevational view being a mirror image thereof;
FIG. 5 is a top plan view of the toolbox of FIG. 1; and,
FIG. 6 is a bottom plan view of the toolbox of FIG. 1.
